UNITED STATES PATENT OFFICE

OMER EDWARD HAUBROCK, OF BRISTOL, TENNESSEE

SAWMILL

Application filed February 3, 1932. Serial No. 590,891.

The present invention relates to saw mills and has for its primary object to provide, in a manner as hereinafter set forth, an apparatus of this character embodying a plurality of complete mobile units adapted to be readily transported from place to place and expeditiously coupled together at any desired point in a manner to provide a complete saw mill.

10 Another important object is to provide a saw mill of the character described embodying novel means for conveniently coupling the units together for operation and for supporting said units.

15 Other objects of the invention are to provide a saw mill of the character set forth which will be simple in construction, strong, durable, efficient and reliable in operation and which may be manufactured at low cost.

20 All of the foregoing and still further objects and advantages of the invention will become apparent from a study of the following specification, taken in connection with the accompanying drawings wherein like characters of reference designate corresponding parts throughout the several views, and wherein:—

Figure 1 is a view in top plan showing a saw mill in accordance with this invention, 30 the units being assembled and ready for operation.

Figure 2 is a view in side elevation thereof.

Figure 3 is a view principally in end elevation and partially broken away in vertical 35 transverse section showing the means for connecting together and supporting in side by side relationship the carriage unit and the saw unit.

Figure 4 is a detail view in perspective of 40 the connecting bar used for coupling the carriage and saw units.

Figure 5 is a detail view in vertical longitudinal section showing the latch means for detachably connecting the units together.

45 Figure 6 is a detail view in perspective of one end portion of the units showing the latch openings.

Figure 7 is a detail view in vertical longitudinal section showing the coupling for

connecting the drive shaft sections of the units together.

Figure 8 is a detail view in vertical section through one of the supporting jacks.

Figure 9 is a view in horizontal section 55 taken substantially on the line 9—9 of Figure 8.

Figure 10 is a detail view in perspective showing additional means for connecting the longitudinally aligned units together. 60

Figure 11 is a detail view in perspective showing a portion of the means for connecting the carriage, saw and edger units together.

Figure 12 is a detail view in front elevation of the latch. 65

Figure 13 is a view principally in top plan and partially in horizontal section of the latch.

Figure 14 is a detail view in perspective 70 showing the upper end portion of one of the jacks.

Referring now to the drawings in detail, it will be seen that the reference character A designates generally a carriage unit, B 75 designates generally a saw unit, C designates generally an edger unit and D designates generally a trimmer unit. Each unit is preferably in the form of a trailer and, in the embodiment illustrated, comprises a frame 1 80 having a platform 2 thereon, said frame being mounted on the supporting wheels 3.

Mounted on the unit B is a saw 4. Although a band saw has been illustrated, it is understood, of course, that a circular saw may be used. An edger mechanism 5 is mounted on the unit C and a trimmer mechanism 6 is mounted on the unit D. Mounted on one side of each of the units B, C, and D is a drive shaft section 7 which extends longitudinally. The shaft sections 7 are journaled for rotation in suitable bearings 8. When the saw mill is assembled, the shaft sections 7 are coupled to each other by suitable means, such as a sleeve 9 having set screws 10 therein, as best seen in Figure 7 of the drawings. In this manner a drive shaft is provided which

95 may receive its power from any suitable source. A carriage mechanism 11 is mounted 100

on the unit A. Said carriage is movable on a railway 12 which projects alongside the unit C, Figures 1 and 2. The carriage mechanism 11 may be actuated in any suitable manner.

5 Referring now to Figures 3 and 4 of the drawings, it will be seen that the forward end portions of the units A and B are connected together by means which includes a bolt 13 extending through the adjacent sides 10 of the frames of these units, a spacer 14 being provided on the bolt between the frames. Extending transversely beneath the forward end portions of said units A and B is a clamp bar 15 having upturned apertured end portions 16 through which the clamping screws 17 are threaded for engagement with the frames for clamping said frames together. At spaced points the lower side of the clamp bar 15 is provided with pairs of sockets 18 for 20 a purpose which will be presently set forth. A similar clamp bar 15 extends transversely beneath the rear end portion of the units A and B, Figure 2.

The adjacent ends of the longitudinally aligned units B, C and D are detachably connected together by means which includes latches 19 pivotally mounted for swinging movement in vertical planes in bearings 20 on one of said adjacent ends, said latches being 25 engageable in openings 21 provided therefor in the adjacent end of the adjacent unit. This is illustrated to advantage in Figure 5 of the drawings. A connecting means for the longitudinally aligned units B, C and D further includes the detachable side plates 22 secured by nut equipped bolts 23 to the sides of the frames of these units. As illustrated to advantage in Figure 11 of the drawings, the rear end of the unit A is connected to the 30 adjacent ends of the units B and C through the medium of an angle iron 24 which abuts the adjacent plate 22 and is secured thereto by the bolt which secures said adjacent plate 22 to the unit C.

45 The units, when assembled, are raised and levelled on the supporting jacks designated generally by the reference numeral 25. The embodiment of supporting jack illustrated comprises a plurality of angle iron legs 26 50 which diverge downwardly from a block 27 having a threaded, vertical bore therein in which is engaged a screw 28. A head 29 is mounted for universal movement on the upper end of the screw 28 and is provided with 55 a pair of upstanding pins 30. Braces 31 are provided for the legs 26. A nut 32 is threaded on the screw 28 and engageable with the block 27 for raising and lowering said screw. The jacks 25 are engaged beneath the clamp bars 60 15, beneath the railway extension 12 and beneath the frames of the units B, C and D in the manner illustrated to advantage in Figures 1 and 2 of the drawings. The sockets 18 in the lower side of the clamp bars 15 are 65 for the reception of the pins 30 on the heads

29 of the screw jacks. The portions of the extensions 12 and the units B, C and D which are engaged by the screw jacks are also provided with pairs of sockets for the reception of the pins. In this manner accidental disengagement of the heads 29 is prevented.

70 The latches 19 and the openings 21 are so formed that when the units B, C and D are moved together, the latches ride upward in the openings and drop to operative position. To this end, the latches 19 include stops 33 engageable with the frames upon which the latches are mounted for supporting said latches in proper position to enter the openings 21.

75 As will be apparent, the units may be conveniently transported from place to place, as a train, being drawn by a single draft vehicle, such as a tractor or motor truck. When the desired location is reached, the units are operatively coupled together or assembled and raised on the supporting jacks 25 and the saw mill is ready for operation. Then, when it is desired to again move to a new location, the supporting jacks are removed, the units are disconnected and coupled together in a train and are ready to be again moved.

80 90 95 100 105 110 115 120 125 130 It is believed that the many advantages of a saw mill constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A saw mill comprising a truck carrying woodworking means, a second truck longitudinally aligned with the first named truck, means connecting the meeting ends of said trucks, a third truck adapted for use in side by side relation with the first named truck, means detachably connecting the first and third named trucks when the third-named truck is alongside the first-named truck, a railway on the third named truck and having an extension disposed alongside the second named truck, a carriage translatable on said railway, jacks complementary to said trucks, and other jacks complementary to said railway extension.

able on said railway, jacks complementary to said trucks, and other jacks complementary to said railway extension; the first and second-named trucks being equipped with 5 longitudinal shaft sections, and means detachably connecting the adjoining ends of said shaft sections.

3. A saw mill comprising a truck carrying 10 woodworking means, a second truck longitudinally aligned with the first named truck, means connecting the meeting ends of said trucks, a third truck adapted for use in side by side relation with the first named truck, means detachably connecting the first and 15 third-named trucks when the latter is alongside the former, a railway on the third named truck and having an extension disposed alongside the second named truck, a carriage translatable on said railway, jacks complementary 20 to said trucks, and other jacks complementary to said railway extension; the means connecting the first and third-named trucks being in the form of transverse bars adapted to be superimposed on and engaged 25 with jacks and being provided with upstanding end portions and screws bearing in said end portions and set against the outer edges of the trucks.

In testimony whereof I affix my signature.
30 OMER EDWARD HAUBROCK.
